UNITED STATES PATENT OFFICE.

JOHN WEST, OF BROOKLYN, NEW YORK, ASSIGNOR TO THE MANHATTAN TYPE FOUNDRY, OF NEW YORK.

DESIGN FOR A FONT OF COMBINATION TYPE ORNAMENTS.

SPECIFICATION forming part of Design No. 17,359, dated May 24, 1887.

Application filed March 15, 1887. Serial No. 231,050. Term of patent 14 years.

To all whom it may concern:

Be it known that I, JOHN WEST, a citizen of the United States, residing at the city of Brooklyn, in the county of Kings and State of New York, have invented a certain new and original Design for a Font of Combination Type Ornament; and I do declare the following to be a full, clear, and exact description of the invention, reference being had to the accompanying specimen or impression, and to the letters and figures marked thereon, which form part of this specification.

My design is clearly shown in the accompanying typographic impression. It consists of a design for a font of type ornaments, and the different members of the font are numbered from 1 to 69 in the accompanying impression.

No. 1 is a figure composed of a short vertical line, to which at the right, and forming an acute angle therewith, a line of similar strength is attached, the whole inclosing three vertical shading-lines.

No. 2 is the reverse of No. 1.

No. 3 is a figure composed of two oblique but essentially vertical lines, between which is placed an ornamental figure composed of a round dot with cusp-like figures on either side thereof.

No. 4 is the reverse of No. 3.

No. 5 is composed of two short vertical lines, between which is placed a four-armed star-like figure consisting of a circular center and elliptical inclosed rays.

No. 6 is a figure comprising two short horizontal lines united by a vertical line, the upper horizontal line being to the left and the lower one to the right of the vertical line.

No. 7 is the reverse of No. 6.

No. 8 is composed of two short horizontal lines parallel and touching each other, in which the lower line is on the normal line of print and to the left of the lower line. No. 9 is the same, except that the upper line is to the right of the lower one. No. 10 is the same as No. 8, except that the upper line is on the normal line of print; and No. 11 is the same as No. 9, with the exception that the upper line is on the normal line of print.

No. 12 is a figure composed of three oblique

lines, of which the one to the left is the larger and has at its foot a fan-like figure. Between the other two oblique lines are placed three dots in a row. These three lines are joined at the top by a curved line slanting to the right downward, and which cuts off from the remainder of the figure a segment of a scroll.

No. 13 is the reverse of No. 12.

No. 14 is a figure composed of two vertical lines, of which the one to the left is the shorter, and which inclose a star-like figure, and are united at their top by a straight line, and to the right of which is joined an oblique straight line sloping downward to a point upon the same horizontal plane as the lower terminals of the two lines first mentioned.

No. 15 is the reverse of No. 14.

No. 16 is a trapezoid having two vertical sides, the left-hand one of which is prolonged.

No. 17 is a figure composed of a vertical line, to which are joined horizontal lines of equal length, and which are united at their farther ends by a concave line, adjacent to which, and at the middle of which, is a short horizontal line terminating in a dot.

No. 18 consists of two horizontal lines of equal length joined at their right ends by a vertical line with a concave curve at its center, to the right of which curve is a short horizontal line terminating in a dot, and to the left of which are two concentric curves.

No. 20 is a figure comprising two lines at right angles with each other, the ends of which are joined by the concave segment of a circle.

No. 21 is a rectangular figure the left vertical side of which is longer than its corresponding right side, and which has joined to it two short horizontal lines, one at each end. The rectangle is divided into two parts by a vertical line, the right-hand part comprising a rectangle containing three dots arranged vertically in a row.

No. 22 is a rhomboidal figure having its two horizontal sides extended to the left beyond the limits of the rhomb until their ends terminate in the same vertical line. The rhomboid is divided by a line parallel to one of the sides into two portions, the left-hand one of which incloses a row of dots.

No. 23 is a figure representing the segment

of a perspective view of a scroll partially unrolled, and No. 24 is the reverse of the same.

No. 25 is a figure consisting of three upright straight lines sloping to the left, the longest of which lines has at its foot a fan-like ornamentation. Between the shorter of the three lines is a row of dots. These lines are joined at the top by a curved line, and the whole so far described is similar to the lower portion of figure No. 12. About this, but reversing the direction of the curve, is a similar and smaller figure, while beyond it are two curved lines forming nearly a right angle.

No. 26 is the reverse of No. 25.

Nos. 27 and 28 are segments of right and left rolled scrolls.

No. 29 is a figure consisting of three upright straight lines sloping from left to right downward and joined at the top by a curved line.

Sloping toward the left between the two shorter of the upright lines is a row of dots.

No. 30 is the reverse of No. 29.

No. 31 is a figure consisting of a short upright straight line sloping from right to left downward and forming an acute angle with a curved line sloping in the reverse direction. Parallel to the straight line several shading-lines are arranged and a row of dots parallel to the curve.

No. 32 is the reverse of No. 31.

No. 19 is a figure consisting of two short horizontal lines parallel to each other, and between which is placed a re-entering barb-like acute-angled figure.

No. 33 is a figure consisting of two parallel horizontal lines of equal length, between which is placed at the left two parallel vertical lines inclosing a row of dots, and at the right a horizontal line terminating in a dot and provided with two barbs, one inside of the limits of the two lines first mentioned and the other touching the same.

No. 34 is a figure consisting of an inverted letter **A** not quite closed at the bottom, the sloping lines of which terminate in horizontal lines, the lowermost pair of which is ornamented with depending triangles the apexes of which are joined by a horizontal line.

No. 35 is the same as No. 16, but of larger size.

No. 36 is the same as No. 19, but of larger size.

No. 37 is a figure resembling an upright figure **A**, having the upper part expanded into an elliptical flat figure and its upright lines terminating in short horizontal lines, the upper pair of horizontals meeting at an acute angle two tangents to the ellipse mentioned.

No. 38 is an enlargement of No. 33, No. 39 of No. 17, No. 40 of No. 21, No. 41 of No. 18, and No. 42 of No. 22.

No. 43 is a figure composed of concave curves inclosing a star-like figure composed of four rays of loops grouped around a small circle.

No. 44 is the combination of No. 42, with the

direction of the straight lines reversed, with a scroll-like figure which terminates the same.

No. 45 is the reverse of No. 44.

No. 46 is the outline of a scroll placed adjacent to a rhombic figure to the left of it, and which incloses an equal-armed cross.

No. 47 is the reverse of No. 46.

No. 48 is an enlargement of No. 16, No. 49 of No. 17, No. 50 of No. 18, (the direction of the same being reversed,) No. 51 of No. 37, No. 54 of No. 38, No. 56 of No. 42, No. 57 of No. 34, No. 58 of No. 36, No. 59 of No. 40, Nos. 64 and 66 of No. 7, and Nos. 65 and 67 of No. 6.

No. 52 is a scroll-like figure, the horizontal curve of which terminates at the top in a horizontal straight line, while within a triangular-shaped figure are two sets of hair-lines concave upward.

No. 53 is the reverse of No. 52.

No. 55 is a circular figure having two short horizontal lines projecting from the right. It incloses an eight-rayed star-like figure centering upon a small circle, each ray consisting of a solid pendant-like figure, and between each two rays of which is a light radial line terminating in a dot at its outer end.

No. 60 is a figure consisting of two parallel horizontal lines joined by an oblique line sloping downward from right to left. At the lower corner is a small ornament resembling the wing of a butterfly. Dependent from the lowest horizontal line is a scroll-shaped figure inclosing an oblique bar shaded with light vertical lines.

No. 61 is the reverse of No. 60.

No. 62 is a figure consisting of a central rectangle inclosing a series of vertical hair-lines on each side of a shaded rectangle, inside of which are light circular spaces inclosing a dot. To the right of the rectangle is a series of parallel horizontal lines terminating in dots at their farthest ends, and at the left of the rectangle is a series of parallel horizontal lines terminating in a rectangular figure shaded by vertical lines. Above and below the left-hand series of lines is a row of dots placed horizontally.

No. 63 is a short horizontal line, and No. 68 is an enlargement of the same.

No. 69 is an **L** formed by a vertical line joining a horizontal one placed to the left of its lowest extremity.

Having shown and described my invention, what I claim as new is—

The design for a font of type ornaments, numbered 1 to 69, comprising straight and right lines and compound curves and angles, substantially as shown and described.

In testimony whereof I affix my signature in presence of two witnesses.

JOHN WEST.
